[57] **CLAIM**

The ornamental design for a face mask for a motorcyclist having a filter pocket, as shown and described.

DESCRIPTION

FIG. 1 is a left side elevation view of a face mask for a motorcyclist having a filter pocket showing my new design, the right side elevation view being the mirror image thereof; FIG. 2 is a top plan view thereof; FIG. 3 is a bottom plan view thereof; FIG. 4 is a front elevation view thereof; FIG. 5 is a rear elevation view thereof; FIG. 6 is a left side elevation view of a second embodiment, the right side elevation view being the mirror image thereof; FIG. 7 is a top plan view of FIG. 6; FIG. 8 is a bottom plan view of FIG. 6; FIG. 9 is a front elevation view FIG. 6; and, FIG. 10 is a rear elevation view of FIG. 6. The head shown in broken lines in FIGS. 1 and 6 is for illustrative purposes only and forms no part of the claimed design. The crosshatch surface shading shown in FIGS. 1-5, 7 and 10 is understood to repeat throughout the indicated area.
